UNITED STATES PATENT OFFICE.

ANDREW DE VRIES, OF SOUTH BEND, INDIANA, ASSIGNOR TO WESTINGHOUSE ELECTRIC AND MANUFACTURING COMPANY, A CORPORATION OF PENNSYLVANIA.

DESIGN FOR A HEAD FOR LIGHTING STANDARDS.

Application filed August 29, 1927. Serial No. 23,240. Term of patent 14 years.

To all whom it may concern:

Be it known that I, ANDREW DE VRIES, a citizen of the United States, residing at South Bend, in the county of St. Joseph and State of Indiana, have invented a new, original, and ornamental Design for a Head for Lighting Standards, of which the following is a specification, reference being had to the accompanying drawing, constituting a part hereof.

The figure is an elevational view of the head for lighting standards showing my new design.

I claim:—

The ornamental design for a head for lighting standards, as shown.

In testimony whereof, I have hereunto subscribed my name this 19th of August, 1927.

ANDREW DE VRIES.
